UNITED STATES PATENT OFFICE.

HARRY V. LANCASTER, OF LOUISVILLE, KENTUCKY, ASSIGNOR TO CHATTANOOGA
IMPLEMENT & MFG. CO., OF CHATTANOOGA, TENNESSEE.

DESIGN FOR A GRATE BASKET.

Application filed January 29, 1929. Serial No. 29,825. Term of patent 7 years.

To all whom it may concern:

Be it known that I, HARRY V. LANCASTER, a citizen of the United States, residing at Louisville, in the county of Jefferson and State of Kentucky, have invented a new, original, and ornamental Design for a Grate Basket, of which the following is a specification, reference being had to the accompanying drawing, forming part thereof.

The figure is a front perspective view of a grate basket showing my new design.

I claim:

The ornamental design for a grate basket, as shown.

HARRY V. LANCASTER.
